COLD FORGING MACHINE

William Edmund Bolland, Nechells, Birmingham,
England, assignor to L. H. Newton & Co., Ltd.,
Birmingham, England

Application December 20, 1943, Serial No. 515,073
In Great Britain March 5, 1943

2 Claims. (Cl. 10—12)

This invention relates to multi-blow cold forging machines of the kind adapted to form hexagonal or other heads on lengths of steel or other metal rod or wire intended to serve as bolts, rivets or the like. At the present time there is used for this purpose a well known two-blow automatic machine consisting of a die, a pair of punches which operate successively on one end of each work piece, a crank-actuated toggle mechanism for imparting the operative movements to the punches, and means for intermittently feeding to the die the metal to be headed. Ordinarily the metal stock is in the form of a coil, and the free end of the coil which is fed into the die serves to eject from the die the previously headed piece which has been severed from the stock by a cutting means forming a part of the machine. The mode of action of the machine is briefly as follows. After a work piece has been fed into the die, it is gripped by the latter, and then the first punch comes into action for forming a swelling on the adjacent end of the work piece, this movement of the slide which carries both punches being effected during one-half of a revolution of the crank which actuates the toggle mechanism. Then the punches are moved relatively to the slide to bring the other punch into position, and during the next half revolution of the crank the second punch causes the final shape to be imparted to the head on the work piece. On release of the work piece by the die it is ejected by the next feed movement of the stock. This machine operates continuously, in that each cycle follows its predecessor without intermission.

A disadvantage of the above described machine is that there is a limit to the length of the work pieces which can be dealt with, this being due to the fact that the finished work piece is ejected automatically by the incoming work piece, and that sufficient space must be allowed between the adjacent ends of the die and punch slide to permit this action. The amount of space permissible sets a limit to the length of the work piece that can be dealt with, and consequently it is impossible with such a machine to forge heads on work pieces exceeding a certain length. The machine, however, possesses great advantages over other forms of heading machines, and the problem to which our present invention is directed is that of constructing a machine which whilst retaining the main advantages of a machine, such as that above described, enables work pieces of any length to be dealt with.

The invention consists of a multi-blow heading machine having in combination a die to and from which work pieces previously cut to the re-

quired length can be fed and removed successively by hand, a slide carrying punches which are movable relatively to the die, a rotary member for actuating the slide, and a clutch for transmitting motion from a source to the said member, the clutch being under the control of the attendant and being adapted to disconnect the said member from the source automatically at the end of each work cycle.

In the accompanying sheets of explanatory drawings:

Figure 1 is a part sectional side elevation, and Figure 2 a part sectional plan, of a two-blow cold forging machine embodying the invention.

Figure 3 is a sectional side elevation taken on the line 3—3 of Figure 2.

Figure 4 is a fragmentary sectional view taken on the line 4—4 of Figure 2.

Figures 5, 6 and 7 are similar fragmentary sectional views drawn to a larger scale than Figures 1 to 4, and illustrating the manner in which the punches act on the work piece.

In carrying the invention into effect as shown, I employ a machine comprising a main frame *a*, a transverse driving shaft *b* carried by bearings *c* on the frame, a horizontally movable slide *e* supported between longitudinal guides *f* on the frame, toggle mechanism *g* through which the slide is operable by a crank *i* on the driving shaft and which serves to impart two operative strokes to the slide in each rotation of the driving shaft, a vertically movable slide *j* mounted on the front end of the horizontally movable slide and carrying a pair of punches *k*, *k'* situated one above the other, link and lever mechanism *m* through which the vertically movable slide is actuated from a cam *n* on the driving shaft to bring the punches successively into an operative position during each rotation of the driving shaft, a die *o* supported by the front end of the frame and having fixed and movable parts *o¹*, *o²* between which the work piece *p* (indicated by broken lines in Figure 1) is gripped whilst being subjected to the action of the punches, and a second toggle device *q* operable through a slidable member *r* and a lever *s* from a second cam *t* on the driving shaft to actuate the movable part of the die.

The machine so far described is of conventional form with the exception that the work-severing means usually employed are dispensed with, and that work pieces (in the form of pieces of metal rod or wire cut to the required length) can be successively inserted into and removed from the die *o* by hand. Thus, in the example shown the workpieces as *p* can be inserted into

and withdrawn from the die o through an opening u in the frame a at the front end of the die, that is, the end of the die remote from the punches k, k^1 . Alternatively the work pieces may be inserted and removed through the upper side of the die. Or they may be inserted through the upper side of the die and allowed to fall out through the underside of the die.

It will be understood that the cavity v in the die o is shaped in the usual manner to enable a hexagonal or other head to be formed on one end of each work piece as p under the successive action of the punches k, k^1 .

Figures 5 to 7 illustrate the manner in which the punches k, k^1 act on the work piece p in the die o . In Figure 5 the first punch k is shown in the operative position which it occupies immediately prior to acting on the work piece p . In this position the punch k is coaxial with the work piece p , the latter having been gripped between the die parts o^1, o^2 with the end to be headed projecting to the required extent from the rear of the die. The operative stroke of the first punch k causes the projecting end of the work piece p to receive a bulbous form as shown in Figure 6, whereupon this punch is withdrawn and the second punch k^1 caused to assume the operative position previously occupied by the first punch. The operative stroke of the second punch k^1 causes the bulbous end of the work piece p to fill the die cavity v and form the required hexagonal or other head on the work piece, this condition being shown in Figure 7.

For determining the extent to which the work piece p projects from the rear of the die o prior to the heading operation, I employ a stop in the form of an arm w on one end of a rod x , the latter being rotatably supported by bearings x^1 so arranged on the frame a at one side of the horizontally movable slide e that by appropriate oscillatory movements of the rod the arm can be moved into and out of an operative position in which its outer end lies opposite to the rear end of the die cavity. Near the end remote from the arm w the rod x is cranked (as shown in Figures 1 and 2) so that this end of the rod can co-operate with a third cam y on the driving shaft b . This cam y serves to move the rod x in the direction for moving the arm into its operative position, the opposite movement of the rod being effected under the control of the cam by a torsion spring z on the rod. When the machine is at rest the arm w occupies its operative position in which it serves as a stop for the work piece being inserted into the die o . At the commencement of each rotation of the driving shaft b the arm w is moved under the action of the spring z to an inoperative position clear of the punches k, k^1 , and at the end of each such rotation the arm is returned by the cam to its operative position against the action of the spring.

For imparting the required motion to the driving shaft b I employ a fly-wheel 2 adapted to be driven continuously by a belt (not shown) from an electric motor or other power source. The fly-wheel 2 is carried by a hollow boss 3 on one side of an annular member 4 which is rotatably mounted on the driving shaft b . If desired the fly-wheel may be rigidly secured to the annular member 4 by a nut 5 , on the outer end of the boss, but preferably annular friction discs 6 are arranged between the sides of the fly-wheel and the adjacent surfaces of the nut and annular member to permit relative rotational move-

ment between the fly-wheel and annular member in the event of the machine being over loaded. At the side remote from the boss 3 the annular member 4 is formed with a recess 7 for accommodating the adjacent side of a second annular member 8 secured on the driving shaft b . The two annular members $4, 8$, form coaxial parts of a clutch which enables the continuously rotating fly-wheel 2 to be connected to the driving shaft b under the control of the attendant, and which automatically disconnects the shaft from the fly-wheel at the end of each rotation of the shaft. The two clutch members $4, 8$ are interconnectable by a spring-loaded key 9 which is mounted in a radial hole in the member 8 and is adapted to engage either of a pair of recesses 10 in the inner periphery of the member 4 . The key 9 is controlled by a catch lever 11 pivoted to a bracket 12 on the frame a , and is adapted to act on a shoulder 13 on the key. The catch lever 11 is operable by a cam-shaped lever 14 also pivoted to the bracket 12 , this latter lever being connected by link and lever mechanism 15 to a pedal 16 . Moreover, the cam-shaped lever 14 is loaded by a spring 17 which is stronger than the spring 18 employed for loading the key 9 , and which serves normally to hold this lever in the position (shown in full lines in Figure 3) in which the catch lever 11 holds the key 9 clear of the inner periphery of the clutch member 8 on the driving shaft b . When the key 9 is in this condition the fly-wheel 2 and the associated clutch member 4 can rotate freely on the driving shaft b .

Depression of the pedal 16 by the attendant serves to move the cam-shaped lever 14 against the action of its loading spring 17 to a position shown in broken lines in Figure 3. The effect of this is to release the key 9 which under the action of its loading spring 18 enters one of the recesses 10 in the rotating clutch member 4 , when the latter assumes an appropriate position, and serves by contact with a hard metal abutment piece 19 in this recess to transmit motion to the other clutch member 8 and the driving shaft b . When the driving shaft b commences to rotate the pedal 16 is released by the attendant, and the ensuing movement of the cam-shaped lever 14 under the action of its loading spring 17 causes the catch lever 11 to assume a position in which it serves automatically to return the key 9 to its initial operative position at the end of a complete revolution of the driving shaft b , thus bringing the machine to rest. During this revolution of the driving shaft b a work piece is headed as previously described, and when the machine is brought to rest the headed workpiece is removed from the die o and another work piece is inserted preparatory to the pedal 16 being again depressed to cause a repetition of the above described operations.

Whilst the rate of output of the machine forming the subject of my invention is less than that of an ordinary two-blow cold forging machine adapted to operate on short work pieces, it is nevertheless much greater than that of other means or methods at present used for heading long work pieces, and moreover it enables the same high quality of performance to be obtained as is produced by the usual two-blow machines. The invention is not, however, limited to two-blow cold forging machines, but may be applied to three-blow or other multi-blow cold forging machines.

Having thus described my invention what I

claim as new and desire to secure by Letters Patent is:

1. A multi-blow cold forging machine of the kind specified, having in combination a die to and from which work pieces previously cut to the required length can be fed and removed successively by hand, a slide carrying punches which are movable relatively to the die, a rotary member for actuating the slide, and a clutch for transmitting motion from a source to the said member, the clutch comprising a pair of coaxial parts, a spring loaded key for interconnecting the said parts, and means whereby the key can be moved against the action of its spring loading into an inoperative position both under the control of the attendant at the commencement of each work cycle, and automatically at the end of each work cycle.

5 2. A multi-blow cold forging machine of the kind specified, having in combination a die to and from which work pieces previously cut to the required length can be fed and removed successively by hand, a slide movable relatively to the die, punches carried by the slide and movable relatively thereto so as to act in succession on each work piece fed to the die, a rotary member for actuating the slide, and a clutch adapted to 10 be brought into action under the control of the attendant for transmitting motion from a source to the said member, and to be put out of action automatically after the punches have performed their function on a work piece.

15 WILLIAM EDMUND BOLLAND.
